MECHANISM AND SYSTEM FOR TRANSMITTING MESSAGES

August D. Eitzen, Rockville Centre, N. Y., assignor
to News Projection Corporation, New York,
N. Y., a corporation of New York

Application April 20, 1933, Serial No. 666,978
Renewed January 12, 1937

3 Claims. (Cl. 178—6)

This invention relates in general to message transmitting systems and the mechanism for transmitting and receiving messages and more especially to machines for transmitting and receiving messages in which the transmitting machine translates a printed message on a tape into light impulses, and electrically transmits such light impulses to a remotely disposed receiver which in turn transmits such light impulses onto the screen as images of the printed message.

Among the objects of the present invention, it is aimed to provide an improved message transmitting and receiving mechanism by means of which a printed message on a tape may be transmitted to a remotely disposed screen by translating images of the characters on a printed tape into light impulses, and electrically transmitting such light impulses to a remotely disposed receiver which in turn translates such latter light impulses onto such remotely disposed screen into the images initially produced.

It is still another object of the present invention, to provide an improved message transmitting system especially adapted as an inter-office communication system comprising a transmitting station at which a printed tape or sheet is received, the images of the printed matter on the tape translated into light impulses and such light impulses electrically transmitted to a receiving station, a screen at such receiving station, and means for translating the received light impulses onto such screen into reproductions of the images initially produced at such sending or transmitting station.

These and other features, capabilities and advantages of the invention will appear from the subjoined detail description of specific embodiments thereof illustrated in the accompanying drawings in which

Figure 1 shows more or less diagrammatically a complete message and transmitting system made according to one embodiment of this invention;

Fig. 2 is an enlarged fragmental detail, partly in section showing part of the mechanism for translating images into light impulses or for translating light impulses to images according to the embodiment illustrated in Fig. 1;

Fig. 3 is a plan view of a scanning disc and its position relative to the tape to be scanned according to the embodiment illustrated in Fig. 1;

Fig. 4 is a fragmental sectional elevation more or less diagrammatically shown of another embodiment of the present invention;

Fig. 5 is an enlarged fragmental detail show-

ing the driving mechanism between the motor and the scanning device of the embodiment illustrated in Fig. 4;

Fig. 6 is a section on the line 6—6 of Fig. 4; Fig. 7 is a plan of a scanning disc to be used with the embodiment illustrated in Fig. 4;

Fig. 8 is an enlarged fragmental detail partly in section showing part of the mechanism for translating images into light impulses or for translating light impulses into images according to the embodiment illustrated in Fig. 4; and

Fig. 9 is a perspective of a desk equipped with a receiving set associated therewith forming a part of the present system.

With the embodiment illustrated in Figs. 1 to 3, there may be used any suitable printer, as for instance the high speed ticker which operates and discharges tape at a rate of about sixty-two inches per minute or about one inch of eight characters per second, there being shown in the present instance a ticker 1 for printing on narrow tape 2, such as ticker tape, which tape extends from the ticker 1 under the finger or roller 3 of a switch arm 4 and then over the rollers 5 and 6 disposed at the ends of a light aperture formed above the condenser 7.

From the roller 6, the tape 2 passes down under the idler 8 and then over to the idler 9 of a tape puller 10 having a tape pulling roller 11. The tape passes from the idler 9 over the tape pulling roller 11 down to and under the idler 12 and from the idler 12 over to the rewind reel 13.

The shaft of the tape pulling roller 11 is operatively connected to the motor 14 which is connected by the conductor 15 to a source of electric energy by the outlet plug 16 and also connected to the switch box 17 operated by the switch arm 4. The rewind reel 13 is connected by the flexible belt 18 with the pulley 19 operatively connected to the shaft of the tape pulling roller 11 in the usual way.

For maintaining the tape in driving connection with the tape pulling roller 11, the spring pressed idler 20 is provided.

The condenser 7 is mounted at the upper end of a lamp housing 21 having a lamp 22. Above the scanning disc there is mounted a funnel 23 at the upper end of which there is formed a light sensitive element, such as a photoelectric cell 24 shielded from all extraneous light except that which may pass up to it through the funnel 23 from the lamp 22. The photoelectric cell 24 is connected by the conductors 25 and 26 with the amplifier 27 of usual construction, which in

turn is connected to the main conductors 28 and 29. The main conductors 28 and 29 are connected by the conductors 30 and 31 respectively with the lamp 32 preferably of the rapidly modulating type, such as a neon tube.

5 The lamp 32 in the present instance is mounted in a lamp housing 33 having a condenser 34 at the upper end adjacent to a light aperture from which the light passes to an objective 35 10 and from there to a screen housing 36 having a reflector not shown, ultimately striking the screen 37.

If desired, any number of receiving stations 15 may be provided in which the conductors 28 and 29 may as an instance be connected to other amplifiers denominated generally as n , which amplifiers n are connected to main conductors 38 n and 39 n which main conductors are in turn connected by the conductors 40 n and 41 n respectively with the lamps 42 n preferably of the neon type.

Cooperating with the lamp 22 and photoelectric cell 24, there is provided a disc 43, such for instance as a scanning disc of the Nipkow type. 25 Cooperating with the lamp 33, there is provided a similar disc 44. These discs are substantially identical in construction and are adapted to be operated at the same speed, for which purpose these discs 43 and 44 are preferably operatively connected to the synchronous motors 45 and 46 respectively operating in the well known manner on alternating current.

In the present instance, the discs 43 and 44 are directly mounted on the shafts of the motors 35 45 and 46 respectively. The motors 45 and 46 are connected to the main conductors 47 and 48, the conductors 49 and 50 connecting the motor 45 with the conductors 47 and 48 respectively and the conductors 51 and 52 connecting 40 the motor 46 with the conductors 47 and 48 respectively. The conductors 49 and 50 are preferably provided with the switch 53 and the conductors 51 and 52 with the switch 54.

The discs 43 and 44 are substantially identical in construction having, see Fig. 3, a spiral 45 row of holes 55. In the present instance, there are provided sixty-four of these holes, each being about one sixty-fourth of an inch at the lower end of the disc and flaring outwardly into a 50 cone shaped opening, such as illustrated in Fig. 2, to facilitate the ready passage of a beam of light from the condensers 7 and 34 upwardly therethrough.

In the enlarged detail illustrated in Fig. 2, the 55 condenser 7 is directing a beam of light through the hole 55 of the disc 43 from which it will appear that the full beam of light received at the lower end of the hole 55 will be permitted freely to pass up to the photoelectric cell 24 without 60 interference. The space between successive holes 55 will depend upon the width of the tape submitted. Preferably the space is just sufficient to correspond to the width of the tape so that one hole will entirely clear the tape before the 65 other hole starts to close it, see particularly Fig. 3.

Excellent results have been produced when the speed of the motor approximates eighteen hundred revolutions per minute. After the discs 70 are synchronized so that the spirals S have corresponding openings 55 at the same position on the light aperture, the mechanisms are ready for transmitting and receiving operation. In order that the discs become so synchronized, it will of 75 course be necessary to position the disc 44 so

that its spiral S will correspond to the angular position of the spiral S on the disc 43 corresponding to the light aperture. For so setting the disc 44, it will only be necessary to turn the worm 65 in mesh with the worm wheel 66 on the field frame of the motor 46 properly to position the disc 44, that is to frame the picture.

The operation is substantially as follows, the tape 2 to be used is preferably of a translucent or transparent type through which a light beam 10 freely passes in order to produce images of any printed characters upon the same. If for instance the tape being used is ticker tape as illustrated in Fig. 3, the light from the lamp 22 15 will illuminate the tape 2 and pass through the same only being obstructed where printed characters are positioned. The spiral S from end to end of the same in the present instance is illustrated as scanning a portion of the tape 2, one inch in length, see for instance the area 67 20 in Fig. 3 as a result of which in the fraction of a second in which this area is scanned light impulses corresponding to this area will be transmitted to the photoelectric cell 24 which impulses in turn will be electrically transmitted to the 25 lamp 32 so that the lamp 32 will be illuminated and shut off to correspond to the light impulses transmitted to the cell 24 in turn to cooperate with the openings 55 in the disc 44 to permit light to pass through such openings 55 only as 30 and when light beams pass through corresponding openings 55 of the disc 43 in turn to reproduce an image of the characters on the tape 2, which image will be magnified by the objective 35 and directed ultimately to appear on the 35 screen 37.

In the embodiment illustrated in Fig. 4, there is shown a mechanism which will scan a length of tape at least twice the length of that ordinarily possible with the embodiment illustrated 40 in Fig. 1.

Furthermore, with the embodiment illustrated in Fig. 4, there is shown a mechanism whereby the discs of the receiving station may automatically be adjusted into picture frame relation 45 with the discs of the sending station.

In this embodiment, the tape T may be printed by the ordinary printer, such as a teletype or ticker and free to pass over the guide roller 68 of the switch box 69 and then under the finger 70 of the switch arm 71 pivotally mounted on said switch box 69 and from the finger 70, the tape T passes up to and over the idler 72 at the entrance end of the light aperture formed above the condenser 73. The tape then passes across 55 the idler 74 at the discharge end of the light aperture and then passes down under the idler 75, in the present instance, secured to one side of the lamp housing 76 and from there passes to and under the idler 77 secured to the tape 60 puller 78 and from such idler 77 passes over the pulling roller 79 and then under the idler 80 over to a suitable rewind reel or the like not here shown.

The tape pulling roller 79 is drivingly connected in the usual way to a motor 81, the conductor 81^a of which is connected to a suitable source of power by means of the outlet plug 82 and also connected to the switch box 69 to be controlled by the same.

For drivingly pressing the tape into engagement with the pulling roller 79, there is provided the spring pressed idler 83.

In the lamp housing 76, there is mounted a lamp 84 for directing a beam of light onto the 75

condenser 73 from which the same will pass through the discs hereinafter to be described to a light sensitive device such as the photoelectric cell 85 mounted in the bracket 86 extending up from the side of the lamp housing 76. The 5 photoelectric cell 85 is connected to the main conductors 87 and 88 which are in turn connected to the receiving sets, one receiving set being shown to which the conductors 87 and 88 are initially connected by the conductors 89 and 99 which pass from the conductors 87 and 88 respectively to the amplifier 91, which amplifier 91 is in turn connected by the conductors 92 and 93 to the lamp 94 mounted in the lamp housing 95. 10 The lamp 94 in the present instance is preferably of the type which can be rapidly modulated, such as a neon tube or the like.

From the tube 94, the light rays pass up through the condenser 96 and then through the 20 receiving set of discs hereinafter to be described to the objective lens 97 and from there directed to the screen housing 98 ultimately to produce an image or picture on the screen 99 of the screen housing 98.

25 In the present embodiment, there are provided a set of discs 100 and 101 for the sending station and another set of discs 102 and 103 for the receiving station. These sets of discs are identical with one another, that is the disc 100 is substantially identical to the disc 102 and the disc 101 is substantially identical to the disc 103.

It is here to be noted that this embodiment distinguishes from the embodiment of Fig. 1 in that each station has two discs instead of only 35 one disc. Each set of discs here is drivingly connected to a motor, the discs 100 and 101 drivingly connected to the motor 104 and the other discs 102 and 103 to the motor 105. These two motors are substantially identical to one another and 40 synchronized with a common generator operating on alternating current, the motor 104 being connected by the conductors 106 and 107 through the switch 108 to the main conductors 109 and 110 and the motor 105 is adapted to be connected 45 by the conductors 111 and 112 through the switch 113 to the main conductors 109 and 110 leading to the common source of current not shown.

In the present instance, the lamp 84 is connected to the conductors 106 and 107 by the conductors 114 and 115 respectively. When the motors 104 and 105 are so connected to the main conductors 109 and 110 and the current is turned on, these motors will synchronize with one another and in turn drive the sets of discs 100-101 and 102-103 respectively at the same speed and 55 therefore in synchronism with one another.

The upper disc of each of these sets in the present instance is connected to be rotated at one half the speed of the lower disc. For this purpose, 60 the motor 104 has its shaft 116 fixed to the lower disc 101, and the upper disc 100 rotatably mounted on this shaft 116 but fixed in its rate of speed relative to the rate of speed of the shaft 116 by a speed reducing train of gears, the shaft 116 having 65 fixed at its upper end a small gear 117 in mesh with the large gear 118 rotatably mounted on the stub shaft 119 fastened in the boss 120 of the bracket 86. The gear 118 has fixed at its lower hub, the gear 121 which meshes with the gear 122 70 fixed to the upper disc 100. The train of gears are selected to reduce the speed by two so that the disc 100 will have a speed relative to the speed of the disc 101 of one to two.

The disc 103 will similarly be fixed to rotate 75 with the shaft 127 of the motor 105 and the disc

102 connected to the gear 123 and the train of gears 124, 125, and 126 with the shaft 127 of the motor so that here too the speed of the disc 102 relative to the speed of the disc 103 will be as one to two.

5 Each of the lower discs 101 and 103 will be provided with a like number of openings 128 formed in the shape of a spiral twice moving around the center of the disc. Each of these openings has a diameter at its lower end of about one sixtieth of an inch flaring outwardly in its upward direction similar to the form of openings 55 of the embodiment illustrated in Fig. 1, see Fig. 2.

The speed of the disc 101 here too is about eighteen hundred revolutions per minute so that 15 the speed of the disc 100 will be about nine hundred revolutions per minute. The openings 128 in the present instance likewise are spaced from one another at least the width of the tape being used so that one opening can entirely clear the 20 tape before the second opening passes onto the tape.

This spaced relation also exists between the first opening at the outer end of the spiral and the last opening at the inner end of the spiral 25 so that the first opening of the spiral at the outer end of the spiral cannot cross the tape until the last opening at the inner end of the spiral has entirely cleared the tape, see the tape area 129 shown in dotted lines in Fig. 7.

30 The upper disc of each set, see the disc 100 in Fig. 7 is provided with a spiral slot 130 having a single convolution as compared to the row of openings 128 in the lower disc 101. This slot 130 has its outer end registering with the outermost opening 128 of the disc 101 relative to the outer periphery of these discs, see Fig. 7 and the inner end of the recess 130 registers with the innermost opening 128 of the disc 101 relative to the outer periphery of these discs, see Fig. 7.

40 From the foregoing, it will thus appear that when the disc 100 makes one revolution to two revolutions of the lower disc 101, the spiral recess 130 will successively register and thus successively expose each of the openings 128 of the spiral 101, 45 beginning with the outermost opening and ending with the innermost opening.

In this way by substantially doubling the number of openings 128 as compared to the number of openings 55 of the embodiment illustrated in 50 Fig. 1 and the cooperation with this auxiliary disc 100 and area of tape, twice the length of the area of tape that can be scanned with the first embodiment can be scanned with the second embodiment in the same period or interval of time. 55 The recess 130 here too may be chamfered if desired, although not absolutely necessary.

60 For automatically synchronizing the two sets of discs, the mechanism now to be described is provided. The lower disc of each of the sets of discs, as an instance the disc 101 will be provided with an elongated slot 131 preferably beyond the end of the outermost end of the spiral row of openings 128, which opening is chamfered, the walls flaring outwardly in an upward direction 65 and the upper disc of each of the sets, as an instance, the disc 100 will be provided with a similar elongated slot, to wit the slot 132, see Figs. 7 and 8, the walls of which are chamfered flaring outwardly in an upward direction as indicated. 70 These two slots may register with one another and with the opening 133 formed adjacent to the light aperture 134 above the condenser 73. Preferably the slots 132, 131 and opening 133 have substantially the same width.

The opening 133 similarly may be chamfered and have its walls flaring outwardly in an upward direction so that when these three openings 132, 131 and 133 register with one another, a beam of light may pass from the condenser 73 to the light sensitive element 85 without being obstructed by any portion of the walls of the discs 100, 101 and of the lamp housing 76.

The discs 102 and 103 of the receiving station will be provided with similar openings 132 and 131 respectively and the lamp housing 95 with an opening similar to the opening 133. At the receiving station, however, the light beam passing through these openings when in registration with one another will be picked up by a reflector 134 and by it directed onto a secondary light sensitive device, such as the photo-electric cell 135 mounted on the side of the lamp housing 95 which is connected by the conductors 136 and 137 with the amplifier 138 which is in turn connected by the conductors 139 and 140 with the winding 141 having a solid core 142 and a shading coil 143 to form a slow opening magnet to attract the armature 144 which is connected by the conductor 145 with the conductor 146 connected through the switch 113 with the main conductor 109.

The armature 144 is provided with the contact 147 adapted to engage the contact 148 when the armature 144 is attracted by the core 142. This contact 148 is connected to the conductor 111. The conductor 112 as illustrated may be directly connected through the switch 113 to the main conductor 110. Consequently when the sets of openings 132, 131 and 133 of both the sending station and receiving station register simultaneously, the energization of the core 142 in turn to actuate the armature 144 will close the circuit for the motor 105 so that the motor 105 will only be caused to turn at full speed and therefore in synchronous relation with the motor 104 when the set of discs 102 and 103 are in synchronous relation with the discs 100 and 101.

Initially however when the switches 108 and 113 are turned on, these sets of discs may not be in position to synchronize with one another. During this period, the motor 104 will be connected to turn at its synchronous speed. The motor 105, however, will be connected to run at slightly reduced speed by the means now to be described so as to permit a variation in rotation of the two sets of discs and thus afford an opportunity for the two sets of openings 132, 131 and 133 of the two sets of discs to find one another or rather to permit the set of openings 132, 131 and 133 of the receiving station to assume a position where they will simultaneously register with one another when the openings 132, 131 and 133 of the sending station register with one another.

In order to effect this reduced speed, the conductor 146 is connected to the condenser 149 which is connected to the conductor 150, one end of which is connected to the contact 151 and the other end of which conductor 150 is connected to the winding 152, which winding is connected by the conductor 153 to the conductor 112.

The core 154 of the winding 152 is laminated as shown in Fig. 6 to produce a quick acting magnet. This laminated U-shaped core 154 is in turn connected to the base 155 on which is mounted the laminated leg 156 of the core 154. From the foregoing, it will thus be seen that when the switch 113 is turned on, the current will pass from the conductor 109 through the conductor

146 to the conductor 145 and then through the armature 144 and contact 151 through the conductor 150 and winding 152 to the conductor 153 and conductor 112 back to the main conductor 110 through the switch 113.

During this circuit, it will energize the winding 152 in order to energize the laminated core 154 to attract the armature 144 thereby breaking the contact between the contact 151 and the armature 144 but establishing contact between the contacts 147 and 148 momentarily causing current to pass from the conductor 109 through the switch 113 to the conductor 146 and then through the conductor 145 to the armature 144 and by means of the contacts 147 and 148 to the conductor 111 and thereby to the motor 105, the conductor 112 of the motor 105 being directly connected to the conductor 110 through the switch 113.

However, immediately that the current is so connected with the motor 105, it will be cut off from the winding 152 and since the core 154 is quick acting, it will immediately release the armature 144 and allow the spring 157 to actuate the armature to break the contact between the contacts 147 and 148 and return the armature into engagement with the contact 151 and at the same time again shut the current off to the motor 105.

The condenser 149 of course is provided to quench the sparks produced between the contact 151 and the armature 144. In order to quench the sparks between the contacts 147 and 148, the condenser 158 is provided connected to the conductors 146 and 111.

Due to this intermittent interruption of current to the motor 105, it of course cannot pick up full speed thereby causing the discs 102 and 103 to rotate at a reduced speed.

Note should here be taken of the fact that the retarding action of the core 142 will be so predetermined that it will overlap one revolution of the disc 102, so that when the core 142 has once been energized to attract the armature 144, it will not release the same before the openings 132, 131 and 133 will again register and therefore again impart a light impulse to the cell 131 in turn to reestablish the circuit for the winding 141.

It will of course also be obvious from the foregoing that as the motor 105 will not immediately pick up top speed with the first coincident registration of the two sets of openings 132, 131 and 133 of the two sets of discs, its speed may gradually be built up by successive coincident registrations of these openings and the resulting action aforesaid.

As an instance, the sequence of operation may be substantially as follows, initially the motor 104 may be started by turning on switch 108 and allowed to run at its synchronous speed. The openings 132 and 131 of the discs 100 and 101 of the sending station relative to the opening 133 will come into alignment about nine hundred times per minute. The projected area at the openings 132, 131 and 133 is greater than the area of a scanning hole 128. Preferably this projected area is about ten times greater than a scanning hole 128 and consequently admits a greater amount of light to impinge upon the photo sensitive surface of the cell 85 thereby to produce a very definite strong synchronizing light pulse signal every revolution of disc 100 or nine hundred signal pulses per minute. This synchronizing light pulse signal has a greater light intensity proportionately to the light intensity

of the maximum amount of light that will pass through the scanning hole 128 in proportion as the projected area of the openings 132, 131 and 133 will be to the area of the scanning hole 128.

5 This definite strong synchronizing light pulse signal ten times or more intense than the scanning pulse for the printed image, to wit about nine hundred per minute is sought by the receiving station.

10 The receiving station may now be turned on by actuating the switch 113 in turn to cause current to pass through the motor 105. The current for the motor 105 initially will so be controlled that motor 105 cannot initially come up 15 to synchronous speed although it may closely approach the same. This slightly reduced speed will be accomplished by the vibration of the armature 144 heretofore described. The openings 132, 131 and 133 of the two sets of discs can only 20 line up at their respective starting points, the position illustrated in Figs. 7 and 8, and when the said slightly retarded discs 102 and 103 of the receiving station arrive at the starting point on time, that is at the moment when the strong light pulse 25 signal is sent out from the sending or scanning station through the aligned openings 132, 131 and 133 of the sending station.

From the foregoing, it will thus be apparent, that when a light impulse or light pulse signal 30 passes an opening 128 of the sending station and the openings 132, 131 and 133 of the receiving station register, only a light impulse of low intensity will pass to the light sensitive cell 135 which in turn will not be sufficient to energize 35 the winding 141 to attract the armature 144 to its arrested position and that the winding 141 will only be energized sufficiently to attract the armature 144 into its arrested position when the sets of openings 132, 131 and 133 both of the sending 40 and receiving stations simultaneously register, that is when the strong light pulse signal effected by the set of openings 132, 131 and 133 of the sending station is received by the lamp 94 of the receiving station at the same time that the set 45 of openings 132, 131 and 133 of the receiving station are in alignment.

The aforesaid system is particularly adapted for interoffice communication. As an instance, in a stock broker's office, a ticker may be equipped 50 with a transmitting or sending station and the desk 159 of a broker's office or the like may be equipped with a receiving set having a screen 160 mounted in the upper end of a cabinet 161 as illustrated in Fig. 9. In this way, a single ticker 55 may serve a large brokerage office and the news transmitted by the ticker simultaneously transmitted to a large number of widely separated offices or desks too far removed from the ticker convenient to inspect the same. On the other 60 hand, it is of course obvious that a brokerage concern having several branch offices in different parts of the city or located in different cities will be in a position to effect a material saving in ticker expense since with this system, a single 65 ticker at one office may be connected by this system simultaneously to transmit the messages received to any and all of the branch offices.

I claim:

1. In a transmitter, the combination with a 70 translucent tape having light interrupting characters intermittently printed thereon and discharged in a substantially horizontal plane by a printer, of a horizontally extending light aperture disposed adjacent to the discharge end of the printer, a light sensitive device, means for

drawing the tape between said light sensitive device and said light aperture and across said light aperture as it is discharged by the printer, a pair of adjacent discs concentric to one another mounted to rotate about a vertical axis disposed beyond the discharge end of said light aperture, there being a spiral row of openings formed in two convolutions of the outer zone of one of said discs, there being a spiral slot in a single convolution of the outer zone of the other of said discs, 10 means for drawing the tape between the path of movement of said discs and said light aperture and across said light aperture as the tape is discharged by the printer, a motor, and means for drivingly connecting said discs with said motor 15 so that the outer zones of said discs may move in horizontal paths of movement between said light sensitive device and said tape adjacent to the tape, the driving connections of the disc having the spiral slot causing said disc to rotate at 20 about half the speed of said first disc and said spiral slot being positioned relative to the spiral row of openings of said first disc successively to uncover said openings one at a time thereby to scan successive lineal areas of the tape portion 25 at said light aperture in turn to transmit to said light sensitive device lines of light as light impulses corresponding to the message formed on the tape after the characters are printed on the tape by the printer. 30

2. The combination with a transmitting station comprising a light sensitive device, a source of light for directing light through successive portions of a translucent tape having light interrupting characters printed thereon, a disc having a 35 spiral row of openings, means for rotating said disc to cause said row of openings to scan successive lineal areas of the tape in turn to transmit light from said light source to said light sensitive device as light impulses corresponding to the 40 message formed on the tape, of a receiving station having a screen, and a neon lamp, means for electrically transmitting said light impulses to said neon lamp, means for positioning said light impulses corresponding to the position thereof in 45 said illuminated picture, said positioning means comprising a second disc having a spiral row of openings, means for rotating said second disc to permit the passage of successive lines of light to said screen corresponding to the message transmitted as light impulses, the rotating means at 50 said transmitting and receiving stations being synchronous motors, and means for automatically setting said discs to synchronize, said setting means consisting of an auxiliary opening in each 55 of said discs positioned adjacent to the beginning of its spiral row of openings, a second light sensitive device at said receiving station, means for directing a light beam from said neon lamp at said latter light sensitive device when said auxiliary openings register with said neon lamp, means including an intermittent current interrupter at said receiving station for initially electrically connecting the motor of said receiving 60 station when the current for the motor of the 65 transmitting station is established, and means including a slow opening magnet cooperating with said interrupter and establishing a continuous current to the motor of the receiving station operatively connected to be energized when the auxiliary openings of said transmitting and receiving stations simultaneously register in light receiving 70 position.

3. The combination with a transmitting station comprising a light sensitive device, a source of 75

light for directing light through successive portions of a translucent tape having light interrupting characters formed thereon, a disc having a spiral row of openings, means for rotating said disc to cause said row of openings to scan successive lineal areas of the tape in turn to transmit light from said light source to said light sensitive device as light impulses corresponding to the message formed on the tape, of a receiving station having a screen, and a lamp, means for electrically transmitting said light impulses to said lamp, means for positioning said light impulses corresponding to the position thereof in said illuminated picture, said positioning means comprising a second disc having a spiral row of openings, means for rotating said second disc to permit the passage of successive lines of light to said screen corresponding to the message transmitted as light impulses, the rotating means at said transmitting and receiving stations being synchronous motors, and means for automatically setting said

discs to synchronize, said setting means consisting of an auxiliary opening in each of said discs positioned adjacent to the beginning of its spiral row of openings, a second light sensitive device at said receiving station, means for directing a light beam from said lamp at said latter light sensitive device when said auxiliary openings register with said lamp, means including an intermittent current interrupter at said receiving station for initially electrically connecting the motor of said receiving station when the current for the motor of the transmitting station is established, and means including a slow opening magnet cooperating with said interrupter and establishing a continuous current to the motor of the receiving station operatively connected to be energized when the auxiliary openings of said transmitting and receiving stations simultaneously register in light receiving position.

AUGUST D. EITZEN. 20
